UNITED STATES PATENT OFFICE

2,617,120

FOLDING CRIB ATTACHMENT FOR BEDS

William J. Lester, Clearwater, Fla.

Application April 7, 1950, Serial No. 154,475

1 Claim. (Cl. 5—96)

1

The present invention relates to new and useful improvements in cribs and more particularly to a folding crib adapted for attaching to a bed and moved into a collapsed position under the bed.

An important object of this invention is to provide extensible rails supported under a bed and on which a foldable crib is supported for sliding movement into and out of position for placing the crib in a concealed, inconspicuous position under the bed, when not in use, the crib being removable from its support for use independently of the bed, when desired.

A further object of the invention is to provide novel means for raising the crib to support the mattress thereof in the horizontal plane of the mattress of the bed when the crib is in open position.

A still further object is to provide a device of this character simple and practical in construction, which is neat and attractive in appearance, strong and durable, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view.

Figure 2 is a side elevational view.

Figure 3 is a transverse sectional view taken on the line 3—3 of Figure 2.

Figure 4 is a transverse sectional view showing the crib in folded position under the bed.

Figure 5 is a side elevational view showing the crib in folded position.

Figure 6 is an enlarged transverse sectional view taken on a line 6—6 of Figure 2;

Figure 7 is an enlarged transverse sectional view of one of the rails taken on a line 7—7 of Figure 3; and

Figure 8 is an enlarged detail in elevation of the connector plate for the chain which holds the crib in a raised position.

Referring now to the drawings in detail wherein for the purposes of illustration I have disclosed a preferred embodiment of the invention the numerals 5 and 6 designate a pair of extensible rails of angle metal construction, each rail including a fixed section 7 and a sliding section 8.

The fixed sections 7 of the rails are supported on bars 9 suspended under the opposite sides of

2

a bed 10 by means of hangers 11 suitably secured at their upper ends to the side rails 12 of the bed.

The sliding sections 8 of rails 5 and 6 form two of the sides of an angle metal frame 13 having legs 14 at its outer corners to support the outer end of frame 13 on the floor while the inner end of the frame is supported on the stationary sections 7 of the rails 5 and 6, the frame 13 being slidable into and out of position under the bed on the stationary sections 7 of the rails.

A lower crib frame is shown at 15 and an upper crib frame at 16 supported one above the other by corner posts 17.

15 A pair of U-shaped lifts 18 are formed with outwardly extending trunnions 19 at their ends which are pivoted in the inner and outer sides of frame 13 adjacent the opposite ends of the latter while the central or bight portions of the lifts 18 are pivoted in the opposite sides of lower crib frame 15 for raising and lowering the crib frame by a swinging movement of the lift 18 in a direction longitudinally with respect to bed 10.

20 A chain or other suitable flexible member 20 connects the lower crib frame 15 to frame 13 to limit swinging movement of the crib frame downwardly in one direction after the lifts 18 have been moved past a perpendicular position toward the head of the bed, as shown in Figure 2 of the drawing, to thus hold the crib frame in a raised position.

25 A connector plate 20b is attached in an upright position to frame 13 with an arcuate slot 20c in the plate and in which the lower end of chain 20 is slidable to allow movement of the lower end of the chain during raising and lowering of the crib. Chains 20a also hold the crib from side-wise swinging movement when the crib is raised.

30 Foldable sides 21 and ends 22 of a crib are hinged at their lower edges to the sides and ends of the upper crib frame 16 by conventional hinged structures 23 for folding the sides and ends of the crib in an inward direction, one upon the other. The sides 21 and ends 22 of the crib are held in a raised position by catches 24. The side of the crib nearest the bed is folded under the crib mattress when the crib is occupied to afford easy access thereto from the bed.

35 In the operation of the device the crib is collapsed by folding the side and end frames 21 and 22 of the crib inwardly upon a spring and mattress supported on lower crib frame 15 and the crib frames 15 and 16 swung toward the foot of bed 10 on the lifts 18 to lower the crib frame on sliding frame 13. Sliding frame 13 may then

be pushed under the bed 10 on the fixed sections 7 of the rails 5 and 6 so that the folded crib may be supported in a completely concealed position under the bed.

When it is desired to open the crib the frame 13 is pulled outwardly and crib frames 15 and 16 swung upwardly on lifts 18 and the sides and ends 21 and 22 of the crib then raised and secured in their raised position by the catches 24.

The lifts 18 swing the crib frames 15 and 16 upwardly so that the mattress of the crib is supported substantially in the horizontal plane of the mattress of the bed 10.

A stop 25 carried at the inner ends of rails 8 engage rails 9 to hold the frame 13 from sliding outwardly off of rails 7.

The crib may be separated from the bed and moved to any desired location by removing the lower ends of lifts 18 from frame 13.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

A folding crib attachment for a bed comprising a pair of side rails supported under the bed, a frame slidably mounted on said rails for positioning under the bed and for positioning outwardly of one side of the bed, a crib including a bottom and downwardly folding sides and ends, inverted U-shaped lifts pivotally connected to the bottom of the crib with ends pivoted in said frame, said lifts extending transversely of the bed and the crib for swinging upright past vertical position to raise said crib by swinging of the crib longitudinally of the bed, flexible crossed members connecting the sides of each U-shaped lift to prevent side sway of the crib when raised, and a connection between said crib and frame preventing said crib from lowering from raised position.

WILLIAM J. LESTER.
